UNITED STATES PATENT OFFICE.

CHARLES P. MURPHY, OF CLEVELAND, OHIO.

LEAF-SPRING.

1,314,282.

Specification of Letters Patent. Patented Aug. 26, 1919.

Application filed May 13, 1916, Serial No. 97,260. Renewed December 23, 1918. Serial No. 268,089.

To all whom it may concern:

Be it known that I, CHARLES P. MURPHY, a citizen of the United States, residing at Cleveland, in the county of Cuyahoga and State of Ohio, have invented a certain new and useful Improvement in Leaf-Springs, of which the following is a full, clear, and exact description.

This invention relates to leaf springs especially adapted for use in vehicle suspensions. The ordinary leaf springs, as commonly employed for this purpose, are slow in action, are not sufficiently resilient if of the required strength, and are hard to keep properly lubricated, wherefore it is difficult to maintain uniformity of action in such springs. The present invention aims to produce a leaf spring which has none of the above mentioned defects.

20 The invention consists in the construction and combination of parts shown in the drawing and hereinafter described and definitely pointed out in the appended claims.

In the drawing, Figure 1 is a side elevation of the invention in its simple form; Fig. 2 is a side elevation of a somewhat more efficient but somewhat more expensive embodiment of the invention; Fig. 3 is a side elevation of the invention in its most complete form, and when the springs are suitably protected by an external casing from the dust of the road; Fig. 4 is an end view of the spring shown in Fig. 2, and Fig. 5 is a sectional view in the plane of line 5—5 on Fig. 3.

A leaf spring constructed in accordance with this invention includes a plurality of normally bent spring leaves, viz., a master leaf 10, and a plurality of supplemental leaves 12. At a suitable point in the lengths of these leaves, preferably at their middle points, they are all rigidly clamped together, as by any suitable clamp 15 the parts of said leaves within the embrace of the clamp being fitted to one another.

These supplemental spring leaves 12 are of progressively increasing length, that which is next the master leaf being the shortest. At or very near their ends each of these supplemental spring leaves contacts with and presses upon the master leaf. The contact may be direct as shown in Fig. 1, or indirect as through rollers 16 mounted in the ends of the supplemental leaves, as shown in Fig. 2. Between these points of contact and the clamp 15, these spring leaves are nor-

mally out of contact, that is to say, they are so bent that there is intervening space between them, as shown.

The master leaf is prolonged beyond the end of the longest supplemental leaf, and is provided with means, as an ordinary eye 11, by which its end may be connected with either the supporting or supported member of a vehicle. In use the clamped part of the described leaf spring may be suitably connected with the body frame of a vehicle,—in which event the end or ends of the master leaf may be connected by suitable means with the axle of said vehicle.

It is clear that with the described construction each supplemental leaf is free to flex at all points between its end and its clamped part, and that none of these springs is reinforced or stiffened by actual engagement with an adjacent leaf. It is desirable that only the points of contact between the master leaf and ends of the supplemental leaves shall be lubricated. In action the ends of the supplemental leaves will slide more or less upon the master leaf and will therefore tend to wear it. This tendency may be counteracted by means of the construction shown in Fig. 2, that is to say, on each end of each supplemental leaf are two ears 12^a, which receive a bolt 13. Upon this bolt a roller 16 is freely mounted for engagement with the surface of the master leaf. This roller is preferably formed with the two circumferential flanges 16^a separated such a distance that they will lie on opposite sides of the master leaf. These rollers therefore will not only serve to reduce the friction and to increase the resiliency of the structure, but they will likewise prevent any lateral movement of the supplemental leaves relative to the master leaf.

When such rollers are not used, it is desirable and perhaps necessary to use such a clip 26 as is shown in Fig. 1 to prevent relative lateral movement of the leaves. This is, however, the same means which is ordinarily employed for the purpose with the old leaf springs.

In Fig. 3 there is shown a metal casing entirely covering the springs; the purpose of this casing is to keep dust and dirt from settling on them. In the construction shown, in which the spring leaves are clamped together near their middle portions, there is a middle part 20 of the casing member which embraces the clamped part of the

springs and also extends a short distance on each side thereof, said middle casing member being embraced by the same clamp which fastens the spring leaves together. A 5 closed casing member 21 is fitted loosely over each end portion of the leaf spring. At its large end which is adjacent the clamped part of the springs this casing member loosely embraces the end of fixed 10 casing member 20. In the side walls of the member 21 are slots 22 through which passes the bolt 23 by means of which said casing member 21 is pivoted to the fixed casing member 20 in such wise that it may move 15 endwise as well as rock. Holes are also formed in the sides of the casing member 21 in alinement with the eye 1¹ on the master spring so that the same bolt which goes through said eye and serves as the means 20 for connecting said master spring with the axle, will likewise connect the casing member and master leaf. These casing members 21 may contain and will retain a very considerable quantity of lubricant, enough to 25 lubricate the relatively movable contacting surfaces of the leaves, and therefore they may be employed for this purpose as well as for the primary purpose of keeping dust from settling on the spring leaves.

30 Having described my invention, I claim:

1. A leaf spring comprising a master spring leaf and a plurality of supplemental spring leaves which, at certain points in their length, are clamped to each other and to the master leaf,—said supplemental leaves being of progressively increasing length and being arranged with the shortest leaf next to the master leaf and said supplemental leaves being of such shape, substantially as 35 shown, that adjacent their ends they press against the master leaf but are not in contact with each other except at and adjacent the parts which are clamped together.
2. A leaf spring comprising a master 45 spring leaf having a curved middle part and two substantially straight ends, and a plurality of supplemental flat concavo-convex spring leaves which are of progressively increasing length and are arranged with 50 their concave sides facing the master leaf and with the shortest leaf next the master leaf, the middle parts of said master leaf

and supplemental leaves being clamped together, and said supplemental leaves being shaped substantially as shown, whereby all 55 their ends are in contact with the master leaf but that said supplemental leaves are out of contact with one another except at their middle points where they are clamped to the master leaf. 60

3. A leaf spring comprising a master spring leaf, and a plurality of supplemental spring leaves which, at certain points in their length, are clamped to each other and to the master leaf,—said supplemental 65 leaves being of progressively increasing length and being arranged with the shortest leaf next to the master leaf, and said supplemental leaves being of such shape, substantially as shown, that adjacent their 70 ends they press against the master leaf but are not in contact with each other except at and adjacent the parts which are clamped together, a casing member fixed to and embracing the clamped parts of said spring 75 leaves, and a casing member which incloses the ends of said spring leaves and telescopes over the ends of the fixed clamping member and is connected therewith by a pin and slot pivot,—said end casing member having in 80 its sides holes which register with an eye on the end of the master leaf.

4. A leaf spring comprising a master spring leaf, and a plurality of supplemental spring leaves which, at certain points in 85 their length, are clamped to each other and to the master leaf,—said supplemental leaves being of progressively increasing length and being arranged with the shortest leaf next to the master leaf, and said supplemental leaves being of such shape, substantially as shown, that adjacent their 90 ends they press against the master leaf but are not in contact with each other except at and adjacent the parts which are clamped 95 together, a casing member fixed to and embracing the clamped parts of said spring leaves, and a casing member which incloses the ends of said spring leaves and telescopes with the ends of the fixed clamping member and is connected thereto. 100

In testimony whereof, I hereunto affix my signature.

CHARLES P. MURPHY.
